DESIGN FOR A NASAL APPLICATOR

Henry H. Rabbes, Arlington, Va., assignor, by direct and mesne assignments, to Fred W. Christian Jr., Wanda Christian, and Marie M. De Forest, copartners, doing business as Lee De Forest Laboratories, Los Angeles, Calif.

Application October 19, 1944, Serial No. 115,873

Term of patent 14 years

(Cl. D83—1)

To all whom it may concern:

Be it known that I, Henry H. Rabbes, a citizen of the United States, residing at Arlington, in the county of Arlington and State of Virginia, have invented a new, original, and ornamental Design for Nasal Applicator, of which the following is a specification, reference being had to the accompanying drawing, forming part thereof.

Fig. 1 is a perspective view of a nasal applicator showing my new design;

Fig. 2 is a perspective view taken from the end opposite that shown in Fig. 1;

Fig. 3 is a side elevational view of the applicator illustrated in Fig. 1;

Fig. 4 is a side elevational view of Fig. 3 turned 90°;

Fig. 5 is an elevational view of one end of such applicator; and

Fig. 6 is an elevational view of the other end of such applicator.

I claim:

The ornamental design for a nasal applicator, as shown.

HENRY H. RABBES.
